UNITED STATES PATENT OFFICE.

JOHN WILSON GIBBS, OF NEW YORK, N. Y.

DESIGN FOR A HEEL-PLATE

SPECIFICATION forming part of Design No. 24,999, dated December 24, 1895.

Application filed October 18, 1895. Serial No. 566,167. Term of patent 3½ years.

To all whom it may concern:

Be it known that I, JOHN WILSON GIBBS, a citizen of the United States, and a resident of New York, in the county and State of New York, have invented a certain new and original Design for a Heel-Plate, of which the following is a specification, reference being had to the accompanying drawing.

The leading portion of my design consists in a heel-shaped plate provided with a raised bifurcated bar located within the circumference thereof.

A denotes one of my plates, which are ordinarily used in pairs, the said plate being heel-shaped in its general contour.

B is a raised bifurcated bar, the outline of

which falls within the outer contour line of the plate A, thus presenting to the eye the combined effect of a smooth heel-shaped outline and a central raised bar, the outline of the same being entirely within that of the plate.

What I claim is—

The design for a heel-plate substantially as described and shown.

In testimony of the foregoing specification I do hereby sign the same, in the city of New York, county and State of New York, this 9th day of September, A. D. 1895.

JOHN WILSON GIBBS.
